UNITED STATES PATENT OFFICE

2,207,351

STENCILING APPARATUS

John E. McLaughlin, Alton, and Albert S. Jackson, Wood River, Ill., assignors to Owens-Illinois Glass Company, a corporation of Ohio

Application September 27, 1938, Serial No. 231,888

6 Claims. (Cl. 101—124)

The present invention relates to apparatus for decorating, lettering, or otherwise marking the curved surfaces of articles such as bottles, jars and the like by a stenciling process wherein a vitreous enamel composition or paint is forced through the interstices of a stencil screen by the spreading action of a squeegee and is thus forced onto the surfaces of the articles.

The principal object of the invention is to provide a stenciling apparatus which is fully automatic in its operation; which will receive the bottles or other articles at a receiving station on a conveyor in a horizontal or recumbent position properly oriented for decorative contact with a horizontal stencil screen positioned at a decorating station; convey the bottles, properly oriented, to the decorating station; elevate the bottles from the conveyor into decorative contact with the screen to receive the decoration; restore the decorated bottles to the conveyor; convey the decorated bottles through an uprighting zone wherein the bottles are brought into an upright position; and finally discharge the bottles onto a take-out conveyor similarly oriented as regards the decorations thereon from whence they may be removed from the apparatus.

Another object of the invention in an apparatus of the type set forth above is to provide a novel and effective means for facilitating introduction of the bottles into the apparatus properly oriented for cooperation with the stencil screen.

A still further object of the invention is to provide such an apparatus in which there is incorporated a novel means for uprighting the bottles prior to their discharge from the apparatus.

Yet another object of the invention is to provide an apparatus of the character set forth above in which means is provided for preventing decorating material from being forced through the screen interstices in the event that no bottle is presented at the decorating station for decorative contact with the screen.

Other objects of the invention, not at this time enumerated, will become apparent hereinafter.

5 In the accompanying drawings:

Fig. 1 is a front elevational view of a stenciling apparatus manufactured in accordance with the principles of the present invention;

Fig. 2 is a rear elevational view thereof;

Fig. 3 is an enlarged fragmentary top plan view of the apparatus taken in the vicinity of the uprighting zone;

Fig. 4 is an enlarged sectional view taken substantially along the line 4—4 of Fig. 2 with certain parts thereof being shown in elevation;

Fig. 5 is a sectional view taken substantially along the line 5—5 of Fig. 1;

Fig. 6 is a sectional view taken substantially along the line 6—6 of Fig. 2;

Fig. 7 is a sectional view taken substantially along the line 7—7 of Fig. 1;

Fig. 8 is a side elevational view of the structure shown in Fig. 7;

Fig. 9 is a sectional view taken substantially along the line 9—9 of Fig. 1;

Fig. 10 is a sectional view taken substantially along the line 10—10 of Fig. 1;

Fig. 11 is a sectional view taken substantially along the line 11—11 of Fig. 1;

Fig. 12 is a diagrammatic view showing the operative relation between a screen actuating cylinder, a control valve therefor, and a mechanically operated actuating valve for the control valve when the screen is in one extreme position;

Fig. 13 is a diagrammatic view similar to Fig. 12 showing the arrangement of parts when the screen is in its other extreme position;

Fig. 14 is an end elevational view of the control valve diagrammatically represented in Figs. 12 and 13;

Fig. 15 is a sectional view taken substantially along the line 15—15 of Fig. 14;

Fig. 16 is a sectional view taken substantially along the line 16—16 of Fig. 15;

Fig. 17 is a diagrammatic view showing the operative relation between certain valve operated chucks and the control mechanism therefor;

Fig. 18 is a perspective view, enlarged, of one form of cradle unit employed in connection with the present invention;

Fig. 19 is a longitudinal sectional view taken vertically through the cradle unit shown in Fig. 18;

Fig. 20 is a sectional view taken substantially along the line 20—20 of Fig. 19; and

Fig. 21 is a sectional view taken substantially along the line 21—21 of Fig. 19.

BRIEF DESCRIPTION

Briefly, referring to Figs. 1 and 2, the apparatus involves in its general organization a wheeled frame or carrier 20 upon which there is mounted an endless conveyor 21 carrying a series of article holding units or supports 22 which are adapted to manually receive thereon in a horizontal or recumbent position bottles B or other similar articles at a receiving station R and convey the same in succession beneath a set of decorating instrumentalities including a stencil screen 23 located at a decorating station D. The conveyor 25

21 is adapted to periodically be indexed in step-by-step fashion by means of an indexing mechanism 24 located at one end thereof and suitably connected to a motor M by means of which all 5 of the operative moving machine instrumentalities are actuated.

An orienting mechanism 25 located at the receiving station R facilitates proper orientation of the bottles B manually on the units 22 for accurate 10 location of the decorations thereon with respect to the usual mold seams which occur at diametrically opposed points on the bottles.

Means are provided for elevating the horizontal bottles from the units 22 at the decorating station D into contact with the screen and for simultaneously reciprocating the latter to apply the desired decorations to the curved sides of the bottles. After application of the decorations, the bottles are conveyed by the holding units 22 15 through an uprighting zone U wherein the units 22 are tilted through an angle of ninety degrees and the bottles carried thereby become uprighted. After the bottles have become uprighted, they are discharged from the units 22 onto a conveyor 25 26 located in a take-out zone T from which they may be manually removed from the apparatus.

THE INDEXING MECHANISM 24 FOR THE CONVEYOR

Referring now to Figs. 1, 2 and 5, the motor M 30 is connected through a gear reduction device 30 to a horizontal drive shaft 31 which in turn is connected through bevel gears 32 to a second shaft 33 at right angles thereto. The shaft 33 carries a disk 34 to which there is eccentrically 35 connected one end of a connecting rod 35 by means of which the indexing mechanism 24 is actuated.

The conveyor shaft 36 (Fig. 5) of which there 40 are two, and which carries the conveyor sprockets 37 for supporting the dual conveyor chains 38 at the discharge end of the conveyor has pivoted thereto a bell crank lever 39, one arm of which is attached to the connecting rod 35 and the other arm of which carries an actuating pawl 40 (Fig. 45 1) for a ratchet wheel 41 keyed to the conveyor shaft 36. The number of teeth provided on the ratchet wheel 41 and the throw of the connecting rod 35 are regulated so that upon continuous 50 rotation of the horizontal shaft 33, the holding units 22 on the conveyor are advanced in the direction indicated by the arrow in Fig. 1 in step-by-step fashion from the receiving end of the conveyor to the discharge end thereof for operative advancement of the bottles through the 55 machine.

THE BOTTLE HOLDING UNITS 22 PER SE

In Figs. 1 to 11 inclusive a simplified form of bottle holding unit 22 is disclosed. In Figs. 18 60 to 21 inclusive a modified form of adjustable holding unit 22' is shown.

The units 22 are best illustrated in Figs. 5 and 6 and each comprises a base plate 42 which is supported on and bridges the conveyor chains 65 38. Hingedly connected to and normally overlying the base plate 42 is a tiltable plate 43 which carries at opposite ends thereof a neck cradle 44 and a base cradle 45 across which a bottle B is adapted to be loosely supported in the manner 70 indicated. A cam roller 46 carried at the forward end of the tiltable plate 43 is designed for co-operation with a pair of rails 47 and 48 (Fig. 1) by means of which the various positions of the tiltable plate 43 during the uprighting operation 75 are controlled. The rail 48 underlies the conveyor

21 coextensively and serves to support the weight of the tiltable plate 43 when the units 22 are inverted and are returning empty to the receiving station R. A pair of rails 28 which are coextensive with the conveyor 21 serve to support the 5 weight of the conveyor chains 38 and cradle units 22 as the latter move from the receiving zone R to the take-out zone T.

The modified adjustable units 22' are similar in their general construction to the units 22 insofar as the base plate 42', the tiltable plate 43', and the tilting means 46' are concerned. The neck and base cradles 44' and 45' respectively, however, are of an adjustable nature, the former consisting of a pair of diverging movable arms 15 50' that are capable of swinging movement toward and away from each other by means of an adjusting screw 51 and the latter consisting of similar arms 52' likewise adjustable by means of a screw 53'. The arms 52' are provided with 20 opposed holding protuberances 54' which prevent dislodgment of the base of the bottle from the holding units 22' due to machine vibration or to natural acceleration of the units at the commencement of each indexing operation. The 25 neck cradle 44' is adjustable on the tiltable plate 43' toward and away from the base cradle 45' by means of clamping bolts 48'.

THE ORIENTING MECHANISM 25

The bottles B are introduced into the machine two at a time by an operator stationed at the receiving station R. One bottle is placed in each of two adjacent holding units located at the forward end of the machine and the axial position of the bottles is determined by means of a guide bar 27 against which the bases of the bottles are brought to bear. For proper centering of the decorations on the bottles, particularly where multi-color decoration is resorted to, it is 40 necessary to commence application of the design or lettering a predetermined fixed distance from one of the bottle seams. Since, as will appear presently, the stencil screen 23 is adapted to act upon successive bottles brought to the decorating 45 station D in opposite directions, it is necessary for the operator to introduce the bottles of each pair at different angular positions respecting the 50 seams thereof. Toward this end the orienting mechanism 25 is provided.

Referring now to Figs. 1 and 2, the orienting mechanism 25 includes a pair of pivoted arms 55 and 56, each having adjustably secured thereto an extensible pointer 57 adapted to overlie adjacent holders 22 at the receiving station R 55 and indicate the angular position which the bottle seams should assume when a pair of bottles are placed in the holders. The arms 55 and 56 are connected together above and below their pivot points by means of a link 58 while a connecting 60 rod 59 eccentrically connected to a disk 60 driven from the conveyor shaft 36 at the receiving end of the conveyor 21 serves to impart oscillatory movement to the arm 56. Thus it will be seen that the free ends of the arms 55 and 56 periodically move toward and away from each other in 65 timed relation to the indexing of the conveyor and alternately assume positions of convergence and divergence with the pointers 57 overlying the adjacent holders 22 at the receiving station R. 70

THE DECORATING INSTRUMENTALITIES

(a) The squeegee and screen assembly

The decorating instrumentalities (Figs. 1, 2, 3 and 4) at the decorating station D are mounted 75

on a superstructure 61 on the carriage 20 and include the reciprocable stencil screen 23 and a relatively stationary squeegee 62 therefor by means of which vitreous enamel placed on the screen is forced through the interstices thereof and onto the surface of a bottle which is maintained in tangential rolling line contact with the screen therebeneath. The screen frame 63 to which the screen 23 is attached is mounted for both vertical and longitudinal adjustment at the forward side of a screen carriage 64 which is in turn mounted in guideways 65 provided by the superstructure 61 for horizontal reciprocation therein. Limit stops 66 mounted on the superstructure limit the extent of reciprocation of the carriage and determine the extreme positions of the screen.

The squeegee 62 is pivotally suspended from a holder 67 adjustably mounted medially of a tiltable squeegee arm 68 which is pivoted to a rock shaft 69 carried in a stationary bracket 71 mounted on the superstructure 61. A pair of squeegee elevating cams 72 secured to the carriage 64 near opposite ends thereof are adapted to engage the squeegee arm 68 as the carriage approaches either of its extreme positions and raise the arm sufficiently to cause the squeegee 62 to clear the vitreous enamel on the screen 23 in accordance with usual stencil screen practice.

(b) *Control mechanism for reciprocating the screen*

Referring now to Figs. 2 and 12 to 16 inclusive, the control mechanism for reciprocating the screen 23 includes a screen actuating cylinder 75 in which there is disposed a piston 76 provided with a piston rod 77, the free end of which is connected to a depending bracket 78 (see also Fig. 4) mounted on the screen carriage 64. Thus it will be seen that upon reciprocation of the piston 76 in the cylinder 75, reciprocation of the carriage 64 will be effected. Movement of the piston 76 is caused by means of an actuating valve 79 comprising a casing 80 having a valve member 81 slidably disposed therein. Opposite ends of the cylinder 75 are connected by means of conduits *a* and *b* having pressure reducing valves 85 therein, to ports 82 and 83 respectively provided in the wall of the valve casing 80. The casing 80 is provided with exhaust ports 84 and an intake port 86 which communicate with a branch conduit *c* leading from a conduit *d* connected to an air pressure tank 87 mounted on the carriage 20. It will be seen, therefore, that when the valve member 81 is in the extreme position shown in Fig. 12, air under pressure passes from the tank 87, through conduits *d* and *c*, ports 86 and 82 in the valve 79, and conduit *a*, to one end of the cylinder 75 to actuate the piston 76 and reciprocate the stencil screen 23 in one direction. Likewise, when the valve member 81 is in the extreme position shown in Fig. 13, air under pressure passes from the tank 87, through the conduits *d* and *c*, ports 86 and 83 in the valve 79, and conduit *b* to the other end of the cylinder 75 to actuate the piston 76 and reciprocate the screen in the other direction.

Shifting of the valve member 81 in the casing 80 of the actuating valve 79 is controlled by means of a mechanically actuated control valve 88.

The control valve 88 is best illustrated in Figs. 14 to 16 inclusive and comprises an outer casing 89 and an inner rotor 90. Ports 91 and 92 extending through the casing 89 communicate with the atmosphere. Ports 93 and 94 in the casing 89

communicate with conduits *e* and *f* leading to the opposite ends of the casing 89 of the actuating valve 79. The rotor 90 is adapted to be periodically indexed through an angle of ninety degrees and is so designed that upon successive indexing operations thereof communication between the ports 93 and 91, and the ports 94 and 92 is alternately established. Branch conduits *g* and *h* lead from the conduit *d* to ports 95 and 96 in the casing 89. Upon successive indexing operations of the rotor 90, air is admitted through the valve 88 alternately to the opposite ends of the valve casing 89 through the separate paths provided first by the conduits *d* and *g*, ports 95 and 94, and conduit *f*, and secondly, by the conduits *d* and *h*, ports 96 and 93, and conduit *e*.

The mechanism for indexing the rotor 90 of the control valve 88 is illustrated in Figs. 2 and 14. A rock shaft 100 suspended below the carrier 20 is oscillated from the shaft 31 by means of a disk 101 mounted on the latter and to which there is connected an eccentric link mechanism 102. Motion of the rock shaft 100 is transmitted through a link 103 to a ratchet and pawl mechanism 104 mounted on the rotor shaft 105 and including an actuating pawl 106 and a holding pawl 107.

(c) *Mechanism for elevating the squeegee in the absence of a bottle at the decorating station*

Referring now to Figs. 1 and 4, a horizontal arm 110 is adjustably secured to a standard 111 mounted on the superstructure 61 and overlies the squeegee arm 68. A solenoid 112 suspended from the arm 110 has its movable core 113 slidably connected to the squeegee arm 68 and is adapted upon energization thereof to elevate the arm 68 and lift the squeegee 62 out of contact with the screen 23. Energization of the solenoid 112 is effected by the closing of a switch 114 (Fig. 1) which is actuated by a gravity arm 115 under which the holding units 22 and bottles therein pass. The arm 115 normally rests upon the successive bottles passing therebeneath but, in the absence of a bottle on any particular holding unit, the arm 115, having no support, moves downwardly by gravity and closes the switch 114, thus energizing the solenoid and raising the squeegee 62 out of contact with the screen.

THE BOTTLE ELEVATING AND SUPPORTING CHUCKS

Upon indexing of the conveyor 21, the bottles *B* are successively moved on the units 22 to a position beneath the stencil screen 23. A guide bar 28 cooperates with the guide bar 27 in holding the bottles against axial shifting on the units 22 as the bottles approach the decorating station *D*. In order to elevate the recumbent bottles *B* periodically brought to the decorating station *D* into contact with the stencil screen 23 and to maintain the same in tangential rolling line contact therewith, a rotatable tapered head chuck 116 (Fig. 4) and a rotatable and axially shiftable recessed base chuck 117 are disposed at opposite sides of the conveyor 21 and are adapted to engage therebetween successive bottles *B* brought to the decorating station on the holding units 22. By virtue of the tapered portion of the head chuck and the recessed portion of the base chuck and the fact that the common axis of the chucks is slightly above the axes of the bottles *B* on the holding units 22, when the chucks engage a bottle therebetween, the bottle is, by a camming action, elevated slightly and is held in tangential rolling line contact with the stencil screen 23.

The base chuck 117 is mounted on one end of

a hollow rotatable shaft 118 supported in a bearing 119 carried by the superstructure 61 and through which bearing vacuum is applied to the chuck from a branch conduit *m* (see also Fig. 17) leading from a conduit *n* that communicates with a port 120 provided in the casing 121 of a mechanically actuated piston valve 122. The casing 121 of the valve 122 has its lower end open and is provided with a port 123 that communicates with a conduit *o* connected to a vacuum tank 124 mounted on the carrier 20. The valve piston 125 is connected through a piston rod 126 to an actuating lever 127 mounted on the rock shaft 100.

The head chuck 116 is mounted for sliding movement toward and away from the base chuck and is carried at one end of a piston rod 128 carrying a piston 129 enclosed in a cylinder 130. A coil spring 131 disposed in the cylinder normally urges the piston 129 and rod 128 in one direction to move the chuck 116 to a retracted position. A port 132 provided in the cylinder 130 communicates with a branch conduit *p* leading from the conduit *n*.

Movement of the rock shaft 100 is so timed with the various phases of machine activity that immediately after each indexing operation of the conveyor 21, the piston 125 is lowered in the cylinder 121 of the valve 122 and vacuum is applied simultaneously to the cylinder 130 to move the head chuck 116 into engagement with a bottle B and to the base chuck 117. Such application of vacuum to the cylinder and base chuck is effected through the conduit *o*, ports 123 and 120 of the valve 122, conduit *n* and the conduits *m* and *p* respectively. After the decoration has been applied to the bottle, the piston 125 is raised in the cylinder 121 and both the cylinder 130 and base chuck 117 are bled to atmosphere through the respective conduits *m* and *p*, conduit *n*, and port 120.

The shaft 118 has mounted thereon a drum 145 (Figs. 2 and 4). A cord 146 passing around the drum 145 is attached at opposite ends thereof to a pair of depending brackets 147 mounted on the carriage 64. Thus, it will be seen that as the screen 23 moves in either direction the chuck 117 is positively rotated and the bottle B carried thereby is caused to make tangential rolling line contact with the screen 23 in accordance with usual stencil practice.

THE BOTTLE UPRIGHTING AND DISCHARGING MECHANISM

Referring now to Figs. 1, 2 and 7 to 11 inclusive, the rail 47 which cooperates with the rail 48 in controlling the tilting movement of the tilttable plate 43 is provided with an upwardly inclined portion 135 in the uprighting zone U and with a sharp downwardly inclined portion 136 in the take-out zone T. As the holding units 22, with the decorated bottles B thereon, move progressively from the decorating station D toward the uprighting zone U, front and rear guide rods 137 and 138 prevent axial shifting of the bottles in the neck and base cradles 44 and 45. As the holders 22 proceed through the uprighting zone U, the cam rollers 46 ride upwardly on the inclined portion 135 of the rail 47, thus progressively tilting the plates 43 which carry the neck and base cradles 44 and 45. A neck guide rod 141 prevents the necks of the bottles from leaving the neck cradles prematurely during the uprighting operation. The bottles B are therefore gradually brought to an upright position, passing through the stages indicated in Figs. 7 to 11 in-

clusive. To prevent the bottles from sliding by gravity out of the cradles 44 and 45 during the uprighting operation, the rod 138 is inclined downwardly and cooperates with a guide rod 139 in preventing shifting of the bottles.

The conveyor 26 is coextensive with the take-out zone T and is driven by a chain and sprocket mechanism 140 (Fig. 5) from the conveyor shaft 36 at the discharge end of the conveyor 21. The bottles B upon becoming upright are deposited upon the conveyor 26 by gravity and are aligned hereon by the rod 139 which is extended horizontally at one side of the conveyor. The bottles B may be removed from the conveyor 26 manually as soon as they have been deposited thereon but in the event that they are not promptly removed, the cam rollers 46 moving downwardly on the inclined portion 136 of the track 47, cause the tilttable plates 43 to be restored to their normal horizontal position in order that the neck and base cradles 44 and 45 may clear the bottles before rounding the end of the conveyor 21. A portion of the rail 48 overlies a portion of the rail 47 to guide the rollers 46 by confining them to a restricted narrow path of movement.

Modifications may be restored to within the spirit and scope of the appended claims.

We claim:

1. In an apparatus for decorating the cylindrical sides of articles, decorating instrumentalities including a horizontally reciprocable stencil screen, means for reciprocating the latter, a support adapted to receive thereon an article to be decorated in a recumbent position, means for moving the support from a receiving station to a position beneath the screen, means for effecting decorative cooperation between the article and screen when the support is beneath the latter, and a pointer disposed at the receiving station designed for cooperation with the mold seam or other indicating mark on the article to facilitate proper orientation of the article when the latter is placed on the support.

2. In an apparatus for decorating the cylindrical sides of articles, decorating instrumentalities including a horizontally reciprocable stencil screen, means for reciprocating the latter, a support adapted to receive thereon an article to be decorated in a recumbent position, means for moving the support from a receiving station to a position beneath the screen, means for effecting decorative cooperation between the article and screen when the support is beneath the latter, a movable pointer disposed at the receiving station designed for cooperation with the mold seam or other indicating mark on the article to facilitate proper orientation of the article when the latter is placed on the support, and means for shifting the position of the pointer upon each reciprocation of the screen.

3. In an apparatus for decorating the cylindrical sides of articles, decorating instrumentalities including a horizontal reciprocable stencil screen, means for reciprocating the latter, a conveyor, a plurality of supports on the conveyor adapted to receive thereon the articles to be decorated, means for indexing the conveyor to move the supports successively from a receiving station to a position beneath the screen, means for effecting decorative cooperation between the screen and articles on the supports when the latter are beneath the screen, and a pair of movable pointers disposed at the receiving station and designed for cooperation with the mold seams or

- other indicating marks on the articles in adjacent supports to facilitate proper orientation of the articles when the latter are placed on the supports.
- 5 4. In an apparatus for decorating the cylindrical sides of articles, decorating instrumentalities including a horizontally reciprocable stencil screen and a relatively stationary squeegee normally in contact with the screen, means for reciprocating the screen, a plurality of supports adapted to receive thereon articles to be decorated, means for moving the supports successively from a receiving station to a position beneath the screen, means for effecting decorative cooperation between the articles and screen when the supports are disposed beneath the latter, and means for elevating the squeegee out of contact with the screen in the absence of an article on a support beneath the screen.
- 10 5. In an apparatus for decorating the cylindrical sides of articles, decorating instrumentalities including a horizontally reciprocable stencil screen and a relatively stationary squeegee normally in contact with the screen, means for reciprocating the screen, a plurality of supports adapted to receive thereon articles to be decorated, means for moving the supports successively from a receiving station to a position beneath the screen, means for effecting decorative cooperation between the articles and screen when the supports are disposed beneath the latter, and means for elevating the squeegee out of contact with the screen in the absence of an article on a support beneath the screen.
- 15 6. In an apparatus for decorating the cylindrical sides of articles, decorating instrumentalities including a horizontally reciprocable stencil screen and a relatively stationary squeegee normally in contact with the screen, means for reciprocating the screen, a plurality of supports adapted to receive thereon articles to be decorated, means for moving the supports successively from a receiving station to a position beneath the screen, means for effecting decorative cooperation between the articles and screen when the supports are disposed beneath the latter, a solenoid having a movable core connected to the squeegee and adapted upon energization thereof to elevate the squeegee out of contact with the screen, a switch for energizing the solenoid, and an arm connected to the switch and overlying the supports when the latter are disposed beneath the screen and adapted to be engaged by the articles on the supports to prevent actuation of the switch.

JOHN E. McLAUGHLIN.
ALBERT S. JACKSON.
